CLAIM

The ornamental design for a hosel for a golf club head, as shown and described.

DESCRIPTION

FIG. 1 is a perspective view of a hosel for a golf club head showing our new design;

FIG. 2 is a side elevational view thereof; and,

FIG. 3 is a rear view thereof.

The undisclosed bottom plan view is plane and unornamented.

The broken line showing of a golf club head is for illustrative purposes only and forms no part of the claimed design.
